[57] CLAIM

The ornamental design for a boot scraper for attachment to skiis, substantially as shown and described.

DESCRIPTION

FIG. 1 is a plan view of a boot scraper for attachment to skiis showing my new design;

FIG. 2 is a front elevational view thereof;

FIG. 3 is a bottom plan view thereof;

FIG. 4 is a side elevational view thereof;

FIG. 5 is an isometric view of my new design.
